GETTER FOR X-RAY GENERATORS

Zed J. Atlee, Elmhurst, Ill., assignor to General Electric X-Ray Corporation, Chicago, Ill., a corporation of New York

Application May 26, 1939, Serial No. 275,877

4 Claims. (Cl. 250—27.5)

My invention relates in general to X-ray generators, and has more particular reference to the provision of means to facilitate the conditioning of the generator for operation after the same has been fabricated.

An important object of the present invention is to provide "getter" means in an X-ray generator for conditioning the same for operation.

Another important object is to provide an X-ray generator comprising cooperating anode and cathode means enclosed in a sealed envelope, the "getter" being disposed in the envelope in a pocket formed therein remote from the active portions of the anode and cathode means, whereby the actuation of the "getter" may not impair or contaminate the anode and cathode means.

Another important object is to form and arrange the "getter" so that the forces generated in flashing the same will be directed into an envelope pocket and away from the anode and cathode means.

Another important object is to provide "getter" means for X-ray generators comprising a material holder of improved form to direct the flash products away from the active portions of the anode and cathode elements; a further object being to provide a mounting for supporting the "getter" holder on one of the active elements of the X-ray generator, the holder being formed to support the holder element in position remote from the anode and cathode means, as in a pocket formed in the envelope of the X-ray generator.

Another important object resides in using a "getter" material characterized by a reluctance to migrate in the envelope upon flashing therein, the material preferably comprising barium and/or aluminum or other suitable non-migratory material having a high melting point, whereby the end products of the flash may be localized innocuously in the remote envelope pocket in which the "getter" means is preferably mounted.

The foregoing and numerous other important objects, advantages and inherent functions of the invention will become apparent as the same is more fully understood from the following description, which, taken in connection with the accompanying drawing, discloses a preferred embodiment of the invention.

Referring to the drawing,

Figure 1 is a sectional view taken substantially longitudinally through an X-ray generator provided with "getter" means in accordance with the teachings of the present invention;

Figure 2 is an enlarged sectional view taken

along line 2—2 in Figure 1, showing the details of the "getter" means illustrated in Figure 1;

Figure 3 is a sectional view taken longitudinally through the end of an X-ray generator to illustrate a modified form of "getter" means and the manner of mounting the same in accordance with the present invention; and

Figures 4 and 5 are sectional views taken substantially along the lines 4—4 in Figure 3 and lines 5—5 in Figures 2 and 4, respectively.

To illustrate my invention, I have shown on the drawing an X-ray generator comprising a cathode 11 and an anode in spaced-apart relationship and in position to cooperate to cause the anode to function as a source of X-rays when energized by electronic action set up by the operation of the cathode. The anode and cathode are enclosed in a preferably glass envelope 15, being sealed in the envelope at the opposite ends thereof. The envelope, as shown on the drawing, comprises a central enlarged portion 19 formed at its opposite ends with sleeve-like extensions 21. The outer ends of the extensions may be turned inwardly to form reentrant sleeve portions 23 on said envelope, and the active elements of the X-ray generator may be mounted on said reentrant sleeve portion and sealed thereon, as at 17. Although in Figure 1 I have shown only the cathode seal, it will be understood that the anode likewise may be sealed in the opposite end of the envelope in like or other suitable or preferred fashion.

The cathode 11 is preferably provided with a dependent skirt portion 25 extending therefrom within the envelope extension 21 to enclose and form a shield for the seal 17 in order to prevent impingement on said seal of stray electrons liberated within the envelope, thereby preventing the seal from becoming deteriorated through electron impact.

It will be noted that the envelope extension 21 and the reentrant sleeve portion 23 form therebetween an annular space 27 into which the terminal edges of the skirt portion 25 extend. The envelope walls also may be offset, as at 29, so that the terminal portions of said annular space 27 are of restricted character forming a pocket 31.

After the parts 11 and 13 have been assembled within the envelope 15, the device is evacuated by connecting the envelope with exhaust means, such as a molecular pump, the connection being made as at 33.

In conditioning the generator for operation, it is necessary to remove not only all of the gas that is present within the envelope, but also the

occluded gas contained in the anode and cathode and in the material of the envelope itself. If such occluded gases are not removed, they will gradually be released within the envelope and impair the exhausted condition at which the generator is designed to operate.

The removal of the occluded gases is accomplished by baking or otherwise heat treating the entire device at a temperature short of the softening point of the glass, while keeping the exhaust means in operation, and also by heating the electrodes to a high temperature, either by electron bombardment or by placing the electrodes in a magnetic field fluctuating at frequencies of the order of radio frequency.

After all of the occluded gases and other impurities have thus been removed from the envelope, the exhaust connection may be sealed off, as at 34. I propose, as a final step, to volatilize or flash a small quantity of a suitable "getter" 35 within the envelope after the envelope has been sealed, in order to form end products of the "getter" material and any remaining gases, the end products being innocuous and remaining in the envelope.

As a "getter" material, I prefer to employ a metal, such as barium and/or aluminum, and preferably a mixture of the named metals, the "getter" material having a high melting point and being characterized by a tendency to remain immobile in the envelope after being flashed.

The "getter" material 35 is preferably used in finely-divided or powdered form and is supported in a holder 37 which in turn is mounted on a support 39 anchored on one of the active elements of the X-ray generator and preferably on the skirt 25 in position such that the holder 37 is disposed in the restricted pocket 31 in a position as far removed from the active portions of the anode and cathode as is possible.

The support 39 preferably comprises a sheet metal strip suitably secured, as at 51, on the skirt 25 and having an offset portion 53 terminating in a curled mounting forming a seat to which the holder 37 may be secured.

The support 39 and the holder 37 are so formed, arranged and mounted that the flange 49 substantially closes and forms a barrier between the space 31 and the remaining portions of the envelope in which the active elements 11 and 13 of the generator are disposed. The holder 37, moreover, is disposed in the chamber 31 in position such that the flash products will impinge directly upon the facing surface of the envelope portions which define the side of the chamber 31 where said flash products will adhere as a film indicated in dotted lines at 59. The envelope surfaces defining the pocket 31, being at the end of the envelope, comprise a cool region on which flash products will readily condense to form the film 59.

The operation of the "getter" may be accomplished in any suitable or convenient fashion, as by heating the "getter" by inductive action to a temperature above the flash point of the "getter" material. After flashing, the flash products will remain in filmed form, as at 59, in substantially immobile condition and ordinarily will not migrate nor deleteriously affect the operation of the elements 11 and 13.

The "getter" material 35 is preferably arranged within a tubular wire 61 of electrical conducting material, one side of which wire is of reduced section, as at 63. This wire may then be supported in any suitable or convenient fashion

on the support 39, in position such that the portion of reduced section 63 faces into the pocket 31. The "getter" may be flashed by heating the same in its enclosing sheath 61 inductively, whereupon the flash products will be expelled outwardly through the wall of reduced section 63, to form the deposit 59 on the facing pocket-forming walls of the envelope.

Preferably, however, the "getter" is flashed by providing for the heating of the same by passage of an electrical current through the sheath or container 61, and this may be accomplished by anchoring the member 61 at one end on the support 39, and by providing conductor means 65 electrically connecting the other end of the member 61 with a source of "getter" flashing electrical power outwardly of the envelope 19, the conductor means 65 being electrically connected with a seal conductor 67 extending outwardly of the envelope through the seal 69. This seal 69 also contains a ground conductor for electrically connecting the body of the electrode 11, including the skirt portion 25, outwardly of the envelope; and by utilizing this ground conductor and the conductor 67, electrical current for flashing the "getter" may be delivered within the envelope from a suitable external power source.

In certain electrode constructions the "getter" flashing conductor 67 may comprise one of the cathode conductors, and in such constructions it is not necessary to provide an additional seal conductor for the sole purpose of flashing the "getter," but the cathode lead may be used for that purpose.

As shown in Figures 1 and 2, the member 61 may be supported on a guard 73 similar to the guard 37 and having a flange 79 adapted to serve as a guard and prevent the flash products of the "getter" material from passing out of the pocket 31, the support member 73 having a plate portion 71 upon which the member 61 is mounted, the member 61 being electrically connected at one end on the plate 71 and arranged in a spiral coil, as shown.

Means may be provided, if necessary, to support the several coils and insulate the same from the plate 71, as by means of glass beads or pedestals formed on the plate 71 to support the member 61 in place, the free end of the member 61 being connected with the conductor 65.

As shown in Figures 3 and 4, the member 61 is arranged as a substantially annular loop in the annular pocket 31, with the wall portion 63 facing the bottom of the annular pocket, one end of the loop being supported on the member 39 and the other being connected with the conductor means 65. When mounted in such fashion, it is not essential to provide a guard similar to the flange 49 and 79. However, an annular plate 89 forming a guard may be provided, desired, and anchored on the member 39 to extend in the pocket 31, and the member 61 containing the "getter" material may be supported on the annular guard 89 in position between said guard and the bottom of the pocket 31.

The member 61 in such case may be electrically connected at one end on the guard 89 and thus grounded on the electrode body, and the other end of the member 61 may be electrically connected, as shown, with the flash conductor 65. The intermediate portions of the member 61 may be mechanically secured on and insulated from the guard 89 as by means of glass mount-

ings or other suitable supporting and insulating means on the guard 89.

Flashing of the "getter," however, substantially reduces the amount of occluded gas remaining in the envelope and permits the provision of an X-ray generator in which occluded gases will not be liberated during the operation of the tube. Consequently, tubes flashed in accordance with my present invention will operate satisfactorily for extended periods without becoming "soft."

It is thought that the invention and numerous of its attendant advantages will be understood from the foregoing description, and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

The invention is hereby claimed as follows:

1. An X-ray generator comprising co-operating electrodes enclosed in an envelope, means on said envelope forming a pocket having a wall providing a cool zone at an end of the envelope, getter means comprising a tubular sheath forming a holder for getter material, said sheath having a wall of reduced sectional thickness along a side thereof and being arranged in a spiral pancake coil, and means for supporting said sheath in said pocket with the wall portions of reduced section facing the pocket-forming wall.

2. An X-ray generator comprising co-operating electrodes enclosed in an envelope, means on said envelope forming an annular pocket having a wall providing a cool zone at an end of the

envelope, getter means comprising a tubular sheath forming a holder for getter material, said sheath having a wall of reduced sectional thickness along a side thereof and being arranged as a loop extending in the annular pocket, and means for supporting said sheath in said pocket with the wall portions of reduced section facing the bottom of the pocket.

3. An X-ray generator comprising co-operating electrodes enclosed in an envelope, means on said envelope forming a pocket having a wall providing a cool zone at an end of the envelope, getter means comprising a tubular sheath forming a holder for getter material, said sheath having a wall of reduced sectional thickness along a side thereof, means to support said sheath on one of said electrodes, and a guard arranged in the pocket between the sheath and the electrode on which the sheath is mounted.

4. An X-ray generator comprising co-operating electrodes enclosed in an envelope, means on said envelope forming a pocket having a wall providing a cool zone at an end of the envelope, getter means comprising a tubular sheath forming a holder for getter material, said sheath having a wall of reduced sectional thickness along a side thereof, a support electrically connected with one of said electrodes, means to electrically connect a portion of said sheath on said support and to insulate the remaining portions of said sheath from said support, and means sealed in said envelope for electrically connecting a portion of said sheath remote from said support connected portion with a source of getter flashing power outwardly of said envelope.
